UNITED STATES PATENT OFFICE.

JAMES T. COWLEY, OF SYRACUSE, NEW YORK, ASSIGNEE TO THE LAMSON COMPANY,
OF SYRACUSE, NEW YORK, A CORPORATION OF MASSACHUSETTS.

CONTROLLING APPARATUS FOR PNEUMATIC-DISPATCH SYSTEMS.

Original application filed July 12, 1923, Serial No. 651,065, Patent No. 1,586,949, dated June 1, 1926.
Divided and this application filed December 5, 1925. Serial No. 73,357.

This invention pertains to power control apparatus for pneumatic dispatch systems and more particularly to automatic apparatus of the general type disclosed in the 5 patent to Libby 968,576 dated August 30, 1910, wherein the opening and closing of a main valve is determined by fluid motor means actuated by pressure variations in the transmission line, the present application being a division of my application Serial No. 10 651,065 for controlling apparatus for pneumatic dispatch systems, filed July 12, 1923, and patented June 1, 1926, Number 1,586,949.

The principal objects of the present invention are to provide improved controlling apparatus of the above type which is sensitively responsive to slight pressure variations in the transmission tube incident to the introduction of a carrier therein or its delivery therefrom, to provide an arrangement such that the slight movement of a pneumatic, for example a flexible diaphragm exposed to transmission tube pressure which occurs when a carrier is introduced into the 20 transmission tube, will initiate the full opening movement of the main valve; to provide means independent of the aforesaid pneumatic responsive to slight drop in pressure in the transmission line for initiating the 25 closing of the main valve; to provide for the rapid restoration of parts to normal position after the discharge of the last carrier from the transmission tube; and in general to provide an apparatus of simple and reliable character having few moving parts and which occupies a minimum of space.

In the accompanying drawings one desirable embodiment of the invention is disclosed by way of example, and in such drawings,

Fig. 1 is a fragmentary vertical section to enlarged scale, such section being taken on the center line of the main valve and showing the parts in their normal position, the main valve being closed; and

Fig. 2 is a diagrammatic view illustrating a preferred arrangement of electrical circuits employed in the operation of the controlling apparatus.

Referring to the drawings, the numeral 1 indicates the main outer casing of the apparatus, such casing being hollow and providing the chamber 2 which is connected in usual manner by means of a suitable pipe,

not shown, to the suction drum or exhaust 55 of the dispatch system.

Within the casing 1 an inner casing 3 furnishes an inner chamber 4, which communicates by means of a passage 5 with the transmission tube, not shown.

The upper and lower walls of the inner casing 3 are provided with aligned valve apertures which are normally closed by the spaced heads 7 and 8 of a balanced main valve 6. A small passage 9, here shown 65 as formed in the head 8 of the main valve, provides for the movement of a small quantity of air, commonly referred to as the minimum flow, from the chamber 4 to the outer chamber 1. The valve 6 is furnished 70 with a stem 10 suitably guided in an opening in the upper wall 11 of the outer housing or casing 1.

The wall 11 is furnished with an outstanding flange portion providing a seat for the edges of a flexible diaphragm 12 which is clamped to the seat by a cover member 13. The diaphragm 12 separates the space between the cover 13 and the wall 11 into upper and lower chambers 14 and 15 respectively. The chamber 1 communicates with the chamber 14 by means of a passage 16 which opens through the diaphragm 12 at the point 18.

The central part of the diaphragm 12 is 85 clamped between plates 20 and 21 which are secured to the stem 10 by means of a nut 22. A rod 23, forming an extension of the stem of the valve 6, is provided with a nut 24 at its lower end and bears against the nut 22 90 on the upper end of the stem 10. If desired the extension 23 may form an integral continuation of the stem 10. A passage 10^a extends axially along the stem 10 and its continuation 23 and opens laterally with 95 chamber 14 and at its lower end is provided with a lateral branch 15^a opening at the outer surface of the stem but normally closed by the wall member 11.

A coil spring 25 encircles the rod 23 and bears at one end against the nut 24. The upper end of the rod 23 passes through a guide opening in a gland 26 having threaded engagement with a suitable opening in the cover 13 and the upper end of the spring 25 bears against the inner surface of this gland.

The cover 13 supports an auxiliary pneumatic motor comprising an upstanding an-

nular flange 27, here shown as integral with the cover 13, and a cover member 28 suitably secured to the flange 27 and which clamps the edges of a diaphragm 31 against the upper edge of the flange 27. This diaphragm 31 separates the space between the cover member 28 and the member 13 into upper and lower chambers 29 and 30 respectively. The lower chamber 30 is provided with a small port 32 leading to the outer atmosphere while the upper chamber 29 is connected by means of a pipe 33 to the transmission line so that transmission line pressure is always maintained in the chamber 29. The diaphragm 31 is provided with a stem 34 which is guided to slide in a gland 36 and which is held in normal position by means of a spring 35 encircling the stem and bearing against the inner surface of the gland.

The cover 13 of the main motor is furnished with an upstanding boss 37 provided with a guide bore 38 parallel to the stem 10 of the valve and which receives a sliding bar or rod 39. A spring 40 bears against the surface of the bar or rod 39 and tends frictionally to retain the latter in whatever position it may be placed. This rod 39 is furnished with axially spaced stops for example, the upper and lower ends of elongate slot 41 in its outer surface, and is provided at its upper end with a taper cam finger or plug 42. This plug and preferably the entire bar 39 is made of some suitable insulating material.

The upper end of the post or stem extension 23 is provided with a bracket 44, one end of which is disposed within the slot or recess 41 in the rod 39. The bracket 44 is also furnished with an upstanding part 45 to which a cam bar 46 is secured.

The cam bar 46 is furnished with an inclined cam surface 46^a at its upper end.

The main housing 1 is provided with a lateral extending hollow boss 47 providing a cavity 48 which communicates freely with the chamber 15. This cavity 48 communicates with the outer atmosphere through a port defined by an annular valve seat with which a valve 49 cooperates. This valve is normally closed and is furnished with a stem 50 constituting or connected to the core of a solenoid 51.

One terminal of the solenoid windings is connected by a wire 52 to one pole of a battery 53 or other suitable source of electrical energy. The other pole of this battery is connected by wires 54 and 54^a with a resilient arm 55 suitably mounted upon an insulating block 55^a. The free extremity of this resilient arm is arranged immediately above the upper end of the stem 34 of the diaphragm 31 and is furnished with an electrical contact element 56. A cooperating contact element 57 is carried by a flexible

arm 58 parallel to the arm 55 and also mounted upon the block 55^a. The arm 58 is connected by a wire 59 to a wire 60 running to the other terminal of the solenoid windings.

The wire 60 is also connected by means of a wire 65 to a resilient arm 61 suitably supported at one end upon an insulating support and furnished at its other end with the contact member 63. This contact member normally engages a cooperating contact member 64 carried at the lower end of a second resilient arm 62 which in turn is supported at its upper end upon an insulating support. The lower ends of the arms 61 and 62 diverge from each other and are disposed immediately above the upper end of the cam member 42 in such a way that upward movement of the post or bar 39 causes the cam 42 to enter between the contacts 63 and 64 and to separate the latter.

The resilient supporting arm 62 is connected by a wire 66 to another resilient arm 67 supported upon an insulating block 67^a. The lower end of the arm 67 carries an electrical contact 68 and the arm 67 is provided at a point intermediate its length with a cam follower block 68^a having an inclined cam surface engageable with the cam surface 46^a of the cam bar 46. The contact 68 cooperates with an opposed contact 67 carried by a resilient arm 70 also mounted upon the block 67^a. This arm 70 is connected by a wire 71 to the wire 54.

The lower wall of the chamber 15 of the main motor is furnished with a small port 80 leading to the outer atmosphere. A valve 81 is adapted to close this port. This valve 81 is carried by a lever 82 pivotally supported at 83 and provided with a counterweight 84 which tends to swing the lever so as to close the valve 81 against the port 80. A rod 85 preferably secured to the lower plate 21 passes through the port 80 and contacts with the valve 81, normally holding the valve open in opposition to the weight 84. Manifestly the rod 85 might alternatively be secured to the valve or might be independent of both the valve and plate and suitably guided for transmitting movement from the plate to the valve.

In the arrangement thus provided the electrical circuit through the solenoid 51 comprises two loops—the wires 54, 71, 67, 66, 65, 60 and 52 constituting one loop, and the wires 54, 54^a, 59, 60 and 52 constituting the other loop. The contacts 63 and 64 form a normally closed switch in the first named loop of the circuit and the contacts 68 and 69 constitute a normally open switch in the same loop. The contacts 56 and 57 form a normally open switch in the other loop of the circuit.

The operation of the device is substantially as follows: it being understood that

the parts normally occupy substantially the positions shown in Fig. 1 when no carrier is in the transmission tube. When a carrier is introduced into the tube the pressure in the latter drops slightly below normal due to the cutting off of the minimum flow, whereupon the diaphragm 12 immediately flexes upwardly to a slight extent but not sufficient to open the main valve 6. This slight movement is enough to cause the cam member 46 to press resilient arm 67 to the left as viewed in Fig. 1 so as to bring the contact 68 into engagement with the contact 69.

The circuit is thus closed through the first loop as above described, thus energizing the solenoid and thereby lifting the valve 49 to admit atmospheric pressure to the chamber 15. This permits the diaphragm 12 to rise freely to its full extent, thus opening the main valve 6 and connecting the suction drum with the transmission tube. This causes a marked decrease in pressure in the transmission tube resulting in a rapid flow of air sufficient to move the carrier toward its destination. This relatively large decrease in pressure in the transmission tube is transmitted through the pipe 33 to the chamber 29 of the auxiliary motor and thus raises the diaphragm 31. It may be stated at this point that the spring 35 is sufficiently strong to prevent upward movement of the diaphragm 31 except when the main valve is at least partially open and a carrier is in the tube.

As the diaphragm 31 rises it brings the contacts 56 and 57 into engagement, thus closing the circuit through the second loop comprising the wires 59 and 54^a. This action takes place just prior to the full opening of the main valve. As the main valve approaches its fully open position the arm 44 comes into engagement with the upper end of the recess 41 in the rod 39 and moves the latter up sufficiently to insert the cam member 42 between the contacts 63 and 64, thus breaking the circuit which was closed by engagement of the contacts 68 and 69, but since the contacts 56 and 57 have previously been engaged the flow of current through the solenoid is not upward.

When the last carrier discharges from the transmission tube the pressure in the latter increases slightly and the spring 35 immediately restores the diaphragm 31 to its normal position. This breaks the circuit through the solenoid since the contacts 56 and 57 immediately separate and as the solenoid is de-energized the valve 49 closes thus cutting off atmospheric pressure from the chamber 15. As the main valve opened, the port 15^a leading to the passage 10^a was lifted above the upper surface of the wall 11 thus providing a small passage between the chamber 15 and the chamber 14. When

the valve 49 is closed as above described the air from the chamber 15 is gradually sucked out through the passage 10^a until the pressure upon the opposite sides of the diaphragm 12 is substantially equalized when the spring 25 becomes operative to close the main valve. As the diaphragm 12 nears its lowermost position the pin 85 causes the valve 81 to open, thus permitting any air which is trapped in the chamber 15 to be expelled as the main valve comes to its fully closed position.

As the diaphragm 12 moves downwardly the finger 44 engages the lower end of the recess 41 in the member 39 and thus restores the member 39 to its normal position, permitting the contacts 63 and 64 to re-engage while at the same time the cam bar 46 moves downwardly and permits the contacts 68 and 69 to separate. The parts are thus restored to their normal position ready for a subsequent operation.

I claim:

1. Power control apparatus for pneumatic dispatch systems comprising a motor, electro-magnetic means for controlling the operation of the motor, and a circuit closer and a circuit breaker both actuated by the motor.

2. Power control apparatus for a pneumatic dispatch system having a transmission tube, said apparatus comprising a pneumatic motor having a reciprocable element, a controlling valve for the motor, an electro-magnetic device for moving the valve, a normally open electrical circuit including said electro-magnetic device, a circuit closer operable by the reciprocable element of the motor for closing said circuit as the reciprocable element begins its movement in one direction and a circuit breaker also operable by the reciprocable element of the motor for opening the circuit as the reciprocable element approaches the limit of its movement in said direction.

3. Power control apparatus for a pneumatic dispatch system having a transmission tube, said apparatus comprising a pneumatic motor having a reciprocable element, a normally closed controlling valve for the motor, an electro-magnetic device for opening the valve, a normally open electrical circuit including said electro-magnetic device, a circuit closer operable by the reciprocable element of the motor for closing said circuit as the reciprocable element begins its movement in one direction and a circuit breaker also operable by the reciprocable element of the motor for opening the circuit as the reciprocable element completes its said movement, and means for short circuiting said circuit breaker whereby to maintain a closed circuit through the electro-magnetic device so long as a carrier remains in the tube.

4. Power control apparatus for a pneumatic dispatch system having a transmission

- 4 tube and means for creating a carrier propelling air flow therein, said apparatus comprising a motor having a reciprocating element, electro-magnetic means for controlling the operation of the motor, an electrical circuit including said electro-magnetic device, a normally open switch device in said circuit, a normally closed switch device in said circuit, means actuatable by the reciprocable element of the motor as it moves in one direction to close the normally open switch, to hold it closed during the remainder of said movement of the reciprocable element, and to open the normally closed switch, and independent means for maintaining a closed circuit through the electro-magnetic device so long as a carrier remains in the transmission tube.
- 5 5. Power control apparatus for a pneumatic dispatch system having a transmission tube and means for creating a carrier propelling air flow therein, said apparatus comprising a motor having a reciprocating element, electro-magnetic means for controlling the operation of the motor, an electrical circuit including said electro-magnetic device, a normally open switch device in said circuit, a normally closed switch device in said circuit, means actuatable by the reciprocable element of the motor as it moves in one direction to close the normally open switch and to keep it closed during the remainder of the movement of the reciprocating element, means operative by the motor for opening the normally closed switch as said reciprocating element nears the end of its stroke, and means for maintaining a closed circuit through the electro-magnetic device so long as a carrier remains in the transmission tube.
- 20 6. Power control apparatus of the class described comprising a transmission tube, a main valve, a reciprocable stem for the valve, a fluid motor for reciprocating the valve stem, a control valve for the motor, an electro-magnetic device for actuating the control valve, an electrical circuit including said electro-magnetic device, a normally open switch in the circuit, means carried by the main valve stem for closing said switch as the main valve begins to open and for holding said switch closed while the main valve is open, a normally closed switch in the circuit, means actuatable by the valve stem as the valve nears its fully open position to open the latter switch, and means independent of the main valve for maintaining a closed circuit through the electro-magnetic device so long as a carrier remains in the tube.
- 25 7. Power control apparatus of the class described comprising a main valve, a reciprocable stem for the valve, a fluid motor for reciprocating the valve stem, a control valve for the motor, an electro-magnetic device for actuating the control valve, an elec-

trical circuit including said electro-magnetic device, a normally open switch in the circuit, a normally closed switch in the circuit, cam means actuatable by the main valve stem for closing the first switch as the main valve begins to open, other cam means for opening the other switch, lost motion connections between the latter cam means and the valve stem, and pressure actuated means independent of the main valve motor for subsequently breaking the circuit through the electro-magnetic device.

8. Power control apparatus of the class described comprising a main valve, a reciprocable stem for the valve, a fluid motor for reciprocating the valve stem, a control valve for the motor, an electro-magnetic device for actuating the control valve, an electrical circuit including said electro-magnetic device, a normally open switch in the circuit, a normally closed switch in the circuit, cam means actuatable by the main valve stem for closing the first switch as the main valve begins to open, a sliding bar parallel with the valve stem, said bar having a cam element for opening the second switch, said bar also having axially spaced stop elements, an arm carried by the main valve stem, one end of the arm being disposed between said stop elements, and an auxiliary motor controlling a third switch in the circuit.

9. Power control apparatus of the class described comprising a main valve, a reciprocable stem for the valve, a fluid motor for reciprocating the valve stem, a control valve for the motor, an electro-magnetic device for actuating the control valve, an electrical circuit including said electro-magnetic device, a switch in said circuit comprising parallel resilient supports, normally separated contacts carried by the supports, a cam follower block secured to one of the supports, an elongate cam bar carried by the main valve stem and engageable with said cam follower as the valve begins to open whereby to move the contacts into engagement and to hold them in engagement substantially so long as the main valve remains open, and means independent of the main valve and its motor for subsequently breaking the circuit through the electro-magnetic device.

10. Power control apparatus for a pneumatic dispatch system comprising a main valve, a motor for actuating it, an auxiliary valve controlling the motor, electro-magnetic means for moving the auxiliary valve, and a circuit including the windings of the electro-magnetic means, said circuit comprising two branches, one branch being provided with a normally open switch and a normally closed switch and the other having a normally open switch, means actuated by the motor for closing the normally open switch and opening the normally closed

switch of the first branch of the circuit, and independent means for closing the switch in the second circuit before the normally closed switch is opened.

- 5 11. Power control apparatus for a pneumatic dispatch system having a transmission tube and means for creating carrier propelling air flow therein, said apparatus comprising a main valve, a pneumatic for actuating it, an auxiliary valve, a solenoid for moving the auxiliary valve, and an electrical circuit including the windings of the solenoid, said circuit having two branches, a normally open and a normally closed switch 10 in the first branch, a normally open switch in the second branch, means actuated by the pneumatic for successively closing the normally open switch and opening the normally closed switch in the first branch of the circuit as the main valve moves from closed to 15 fully open position, and a fluid motor for closing the switch in the other branch of the circuit and for keeping it closed so long as a carrier remains in the transmission tube.
- 20 12. A power control apparatus comprising a pneumatic motor having a chamber, a diaphragm forming one wall of the chamber,

a port for admitting pressure fluid to the chamber, a valve normally closing the port, and means actuatable by the diaphragm for 20 opening the valve as the diaphragm moves inwardly to decrease the normal capacity of the chamber.

13. A power control apparatus comprising a pneumatic motor having a diaphragm, 25 a port for admitting pressure fluid to one side of the diaphragm, a valve for closing the port, and a pin carried by the diaphragm arranged to project through the port as the diaphragm approaches its limit of motion 30 in one direction for opening the valve.

14. A power control apparatus comprising a pneumatic motor having a pressure chamber closed at one side by a movable diaphragm, a port in the wall of the chamber, a pivotally mounted valve cooperating with the port, a counterweight normally closing the valve, and a pin carried by the diaphragm arranged to project through the port as the diaphragm approaches one limit 45 of its movement to open the valve. 50

Signed by me at Syracuse, New York this second day of December 1925.

JAMES T. COWLEY.
